Primary Examiner — Caron D Veynar*Assistant Examiner* — Martie K Holtje(74) *Attorney, Agent, or Firm* — Carmody & Torrance LLP(57) **CLAIM**

The ornamental design for an air blower, as shown and described.

DESCRIPTION

FIG. 1 is a top, left front perspective view of an air blower showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The dotted lines are intended to show features that are environmental only and form no part of the claimed design.
